[57] CLAIM

The ornamental design for a combined tube and dispensing cap, as shown and described.

DESCRIPTION

FIG. 1 is a front elevational view of a combined tube and dispensing cap showing my new design;

FIG. 2 is a side elevational view, the opposite side being identical;

FIG. 3 is a top plan view;

FIG. 4 is a perspective view; and

FIG. 5 is a sectional view taken along line 5—5 of FIG. 2.
